UNITED STATES PATENT OFFICE.

CARL F. ANDERSON, OF BROOKFIELD, AND LESTER W. KNAPP, OF BERWYN, ILLINOIS,
ASSIGNORS TO CONLON ELECTRIC WASHER COMPANY, OF CICERO, ILLINOIS, A
CORPORATION OF NEW YORK.

CYLINDER COVER FOR WASHING MACHINES.

1,409,911.

Specification of Letters Patent. Patented Mar. 21, 1922.

Application filed August 18, 1919. Serial No. 318,080.

To all whom it may concern:

Be it known that we, CARL F. ANDERSON and LESTER W. KNAPP, both citizens of the United States, residing at Brookfield, in the county of Cook and State of Illinois, and Berwyn, in the county of Cook and State of Illinois, respectively, have invented a certain new and useful Improvement in Cylinder Covers for Washing Machines, of which the following is a full, clear, concise, and exact description, reference being had to the accompanying drawings, forming a part of this specification.

Our invention relates to cylinder covers for washing machines.

Our invention is generally concerned with washing machines of the type employing oscillatory or rotary clothes containers, and aims to provide an improved door or cover member for closing the opening in the container through which the clothes or other articles are inserted.

Heretofore, these covers have been held in place by swivel fasteners and similar devices, which are objectionable for numerous reasons. First, they are either difficult to operate or are insecure because of the swelling tendency of the wood in which they are pivoted, and in the latter case often release the cover when the cylinder is in motion, with a resultant jamming of the cover between the cylinder and the tub. Second, they project from the smooth periphery of the cylinder in an objectionable manner and have a tendency to catch the clothes.

Our invention overcomes these prior objections by providing a cover for washing machine containers which employs a positive locking arrangement between the cover and cylinder. In this novel locking arrangement there is no possibility of the cover becoming accidentally released during the running of the machine, and furthermore, this locking arrangement has an entire absence of projecting parts which might catch the clothes. Though the cover is securely locked against accidental release, it nevertheless can be easily and quickly released and inserted when desired.

In the accompanying drawings we have illustrated one preferred form of our invention;

Figure 1 is a fragmentary plan view of a washing machine cylinder illustrating the removable cover in place;

Figure 2 is an enlarged transverse sectional view of the same taken on the line 2—2 of Figure 1;

Figure 3 is an isolated sectional view taken approximately on the line 3—3 of Figure 2;

Figure 4 is a detail sectional view of the plunger button; and

Figure 5 is a fragmentary sectional view taken on the line 5—5 of Figure 2.

Figure 1 illustrates a fragmentary portion of a washing machine cylinder, adjacent the opening provided for the insertion of the clothes or other articles to be washed. This washing machine cylinder is composed of wood or metal, and comprises the two end heads 6 and 7, joined together by the plurality of spaced slats 8 which are arranged circumferentially about the cylinder. At their ends, the slats 8—8 are set in an annular groove or depression 9 cut in the periphery of each of the end heads 6 and 7. The heads 6 and 7 are preferably turned out in elliptical formation, so as to compensate for the cross grain expansion of the wood. The general elliptical formation of the end heads is disclosed in the application of Conlon and Moran, Serial No. 158,410, filed March 29, 1917, while the machine for making the particular construction of end head above described is made the subject matter of the co-pending application of Carl F. Anderson, filed on August 27, 1920, under Serial No. 406,388.

We may also state that the slats 8 are of the type made by the improved form of wood working machine illustrated in our co-pending application, Serial No. 332,953, filed Oct. 24th, 1919.

The opening in the cylinder, for the insertion of the clothes is defined by two parallel bracing members 12 and 13, which extend longitudinally between the end heads 6 and 7 and are inclined radially inward toward the center of the cylinder as shown in Figure 2. The opposite ends of the bracing members 12 and 13 are preferably secured to the end heads 6 and 7 through suitable mortise and tenon joints 30 (Figure 5). The shoulders 31 adjacent the tenons of these

joints maintain the end heads 6 and 7 in proper spaced relation. In the limited portion of the periphery between the two bracing members 12 and 13, each head 6 and 7 is cut down flush with the groove or depression 9 to form a smooth flat surface for the support of the cover member 14.

The cover member 14 comprises the series of spaced apertured slats 17, similar to the slats 8, and the two segmental cross pieces 15, which connect the ends of the slats 17. The slats 17 are nailed or otherwise secured to the cross pieces 15, and in the locked position of the cover the ends of these slats are arranged to come flush with the outer surfaces of the heads 6 and 7. It will be noted from Figure 2, that directly over the bracing members 12 and 13 are nailed two locking slats, designated 8' and 8" respectively. These locking slats project from the members 12 and 13 in such a manner as to overlap the ends of the cross pieces 15, and normally lock the cover member 14 in the cylinder opening.

The removal of the cover member 14 is effected by the lateral shifting of the same across the cylinder opening, the cover member being shiftable from the full line position, corresponding to the locked condition, to the dotted line position corresponding to the released condition (Figures 1 and 3). It will be noted that the left cross piece 15 is set inward from the end head 6 to allow of this lateral shifting of the cover member. The lower projecting ends of the cross pieces 15 are chamfered off to form beveled tongues 18, which, in the dotted line position of the cover, are adapted to pass through the two tapered slots 19 which are cut in the locking slat 8'. The cover member 14 is normally retained in its locked position with the tongues and slots 18 and 19 out of register, by a spring plunger button 21 which is set into the body of the head 6. The center slot 17' is cut off short to provide an abutment for engaging the plunger button 21. This plunger button comprises a reduced shank 22 which passes down through a sheet metal tube 23, in which is confined a compression spring 24. The lower end of the tube 23 is crimped over to support the spring 24, the upper end of the spring bearing against the enlarged portion 25 of the plunger button. The end of the shank 22 is headed as indicated at 26 to engage the bottom of the tube 23 and retain the button 21 flush with the top of the slat 17'. The upper edge of the tube 23 is rolled outwardly in the form of a bead 27 for preventing the tube 23 from being pressed downwardly in the hole in the head 6. The button 21 is arranged to seat in a depression or counterbore 28 in the periphery of the head.

To remove the cover, the button 21 is depressed and the cover is slid sidewise to

bring the tongues and slots 18 and 19 into register. The free edge of the cover is then raised and the cover is drawn forwardly to withdraw the other ends of the cross pieces 15 from under the locking slat 8". The manner of replacing the cover will be obvious from the foregoing description.

We do not intend to be limited to the specific details shown and described.

We claim:

1. In combination, a horizontal cylinder, adapted to be rotated on its axis, said cylinder having a lateral opening, a cover for said opening, locking means on the cylinder and on the cover adapted to be brought into register to release the cover from the cylinder and secondary locking means for preventing said locking means from coming into register.

2. In combination, a washing machine container having an opening therein for the insertion of clothes, a cover member for closing said opening, guide means for guiding said cover member in lateral shifting movement across said opening, and locking means for locking said cover member over said opening, said locking means being released and engaged by the lateral shifting of said cover member.

3. In combination, a washing machine cylinder having an opening therein for the insertion of clothes, a cover member for closing said opening, said cover member having lateral shifting motion over said opening, and tongue and slot locking means between said cylinder and said cover member adapted to be released and engaged by the shifting motion of said cover member.

4. In a washing machine, a washing machine cylinder having an opening therein for the insertion of clothes, a cover member for closing said opening, co-operating tongues and slots on said container and said cover member, said tongues and slots when in registration permitting insertion or removal of said cover member, and guide means for guiding said cover member in lateral motion to shift said tongues and slots out of registration.

5. In a washing machine, a cylinder having an opening therein for the insertion of clothes, a removable cover member for closing said opening, tongues on said cover member adapted to co-operate with slots in said cylinder for locking said cover member in place, guide means for guiding said cover member in lateral shifting motion for bringing said tongues and slots into and out of registration, and releasable detent means for retaining said cover member in position with the tongues and slots out of registration.

6. In combination, a washing machine cylinder having an opening therein for the insertion of clothes, a cover member adapted to cover said opening, tongues projecting

from said cover member adapted to cooperate with notches provided in the margin of said openings, guide means adapting said cover member for lateral shifting motion 5 across said openings, the shifting motion of said cover member adapted to bring said tongues and slots into and out of registration, and a plunger button engaging said cover member and adapted to retain the same 10 in position with said tongues and slots out of registration.

7. In combination, a washing machine cylinder having an opening therein for the insertion of clothes, said cylinder comprising 15 two end heads joined by a plurality of slats, a cover member adapted to close said opening, said cover member comprising two cross pieces joined by a plurality of slats, said cross pieces having tongues projecting 20 from the edge of said cover member, said tongues adapted to pass through slots cut in the cylinder slats along the margin of said opening, the other end of said cross pieces adapted to engage under the cylinder 25 slats along the other margin of said opening, said cover member adapted for lateral shifting motion in said opening to bring said tongues and slots into and out of registration, and a spring plunger button in the 30 end head of said cylinder and engaging said cover member for retaining the same in its locked position.

8. In combination, a washing machine cylinder having an opening therein for the 35 insertion of clothes, a cover for said opening adapted to have lateral displacement, and means for positively holding said cover in locked position over said opening whereby lateral shifting in either direction to allow 40 outward displacement is prevented.

9. In combination, a washing machine cylinder having an opening therein for the insertion of clothes, a removable cover for said opening, said cover adapted to be removed 45 therefrom by lateral shifting and radial movement relative to said cylinder, said lateral shifting in the direction of dis-

placement being prevented to prohibit accidental radial displacement of the cover.

10. In combination, a cylinder having an 50 opening therein and a removable cover therefor, said cover removed from said opening by lateral displacement, and means adjacent the edge of and lying in the direction of lateral shifting of said cover restraining said 55 lateral displacement.

11. In combination, a cylinder comprising head members and a plurality of spacing members, certain of said spacing members adapted to form a cover for said cylinder, 60 said cover adapted to have lateral movement for removal thereof from said cylinder, and plunger means disposed in one of the head members projecting in the path of said cover to prevent displacement of the same when 65 in position on the cylinder.

12. In combination, a cylinder comprising head members and a plurality of spacing members, certain of said spacing members removable from said cylinder to form a 70 cover therefor, said cover adapted to be laterally shifted when removing from the cylinder, a plunger disposed in one of said heads, and projecting in the path of said cover, said plunger comprising a sleeve member 75 within said head limiting the upward movement of the plunger and confining a spring between the ends thereof, the upper portion of said plunger lying substantially flush with said cover.

13. In combination, a washing machine cylinder having an opening therein for the insertion of clothes, a removable cover for said opening, means disposed within said cylinder preventing outward displacement 85 of said cover, and means lying substantially within the circumferential dimension of said cylinder preventing lateral shifting of said cover.

In witness whereof we hereunto subscribe 90 our names this 12th day of August, 1919.

CARL F. ANDERSON.
LESTER W. KNAPP.
